DOOR OPENING MEANS

Rudolph I. Schonitzer, Shaker Heights, Ohio

Application February 5, 1940, Serial No. 317,296

8 Claims. (Cl. 16—85)

This invention relates to means for automatically effecting the movement of a hinged door, when closed and unlatched, to any desired open position, and for yieldingly resisting the closing of said door from the open position to which it is automatically movable. More particularly, the present invention relates to means for automatically opening, and yieldingly resisting the closing of a door which is so hinged on its supporting structure that the hinge edge wall of said door and the hinge edge wall of the supporting structure therefor are in oppositely positioned or generally abutting relationship when said door is in its closed position, such as the door of an automobile or the like, for example.

Briefly stated, the means here involved, which, for convenience, is hereinafter referred to simply as door opening means, comprises a reciprocable plunger carried by either the door to be automatically opened or its supporting structure, a curved portion carried by the other and with which curved portion said plunger has cooperative engagement, (said curved portion being of concave form in cross-section if said plunger is carried by said supporting structure and being of convex form in cross-section if said plunger is carried by said door), and expandable means effective upon said plunger for bringing about such cooperative engagement. As will hereinafter more fully appear, the effect of the cooperative engagement of said plunger and said curved portion is (1) the automatic movement of said door, when closed and unlatched, to any desired open position, either a partially open position of said door or the fully open position thereof, and (2) the production of a yieldable resistance to closing movement of said door from the open position to which it is automatically movable, which enables said door to be releasably retained in its fully open position, if that is the position to which it is automatically movable, or in a partially open position, if that is the position to which said door is automatically movable and if said door, like most present-day automobile doors, has a normal tendency to close.

Preferably and as here shown, the plunger of the present door opening means comprises or includes a roller or the like for desirable rolling engagement with the curved portion with which it cooperates for door opening and door retaining purposes. Moreover, the curvature (concavity or convexity) of said curved portion is such that the door opening force automatically applied thereto by said plunger, under the influence of the expandable means therefor, is substantially nor-

mal at all times to said curved portion, and conversely, is such that the manual force applied by said curved portion to said plunger, during closing movement of said door (and which effects the "loading" of said expandable means), is substantially normal at all times to the path of reciprocation of said plunger. As a result, the automatic opening of said door and the loading of said expandable means are accomplished in an exceedingly effective and satisfactory manner, as will be readily understood.

If desired, said curved portion may be simply and economically formed as a depression in or as a projection of the hinge edge wall of the structure by which it is carried, as here shown. Moreover, the length or transverse extent of said curved portion (which is either concave or convex in cross section, as heretofore pointed out) may be substantially equal, if desired and as here shown, to the width of the hinge edge wall of the structure by which it is carried, and the path of reciprocation of the plunger which has cooperative engagement with said curved portion may be such that when the door structure is in its closed position, said plunger engages said curved portion toward one end thereof. However, it obviously is not necessary, in order to effect the automatic movement of a door structure to its fully open position, that the length or transverse extent of said curved portion be substantially equal to the width of the hinge edge wall of the structure by which said curved portion is carried, as will be readily understood.

Another feature of the two door opening means here illustrated is that the plunger of each such means is a part of a self-contained plunger unit, which may be easily and conveniently secured to either the door to be automatically opened or the supporting structure therefor, as will herein-after appear.

Other features of the here illustrated door opening means are their structural simplicity; their strong and rugged character, which enables them to have an exceedingly long life in service, without requiring attention from time to time; and the efficiency with which they perform their door opening function and their function of yieldingly resisting door closing movement.

Further features of door opening means embodying the present invention are in part obvious and in part will appear from the following description of two such means as used with automobile doors, reference being had to the accompanying drawing, in which

Fig. 1 is an outside elevation of a portion of a

left front automobile door and an adjacent portion of the automobile body on which said door is hinged, parts of the outer side walls of said door and body portions being broken away to expose the door opening means associated therewith, said door being in its closed position; Fig. 2 is a horizontal sectional view, on an enlarged scale, through said door and body portions, the view being on the line 2—2, Figs. 1 and 3, and 10 three positions which said door occupies during the movement thereof between its closed position and its fully open position (the position to which said door is here automatically movable) being indicated in dotted lines; Fig. 3 is an outside elevation of said door and body portions, as viewed from the line 3—3, Fig. 2, with parts of the outer side walls thereof broken away to expose said door opening means; Fig. 4 is a side elevation of the self-contained plunger unit of 20 said door opening means, as viewed from the line 4—4, Fig. 2, parts of said plunger unit being broken away and in section; Fig. 5 is a cross-sectional view of said plunger unit, on the line 5—5, Fig. 2, and Fig. 6 is a view similar to Fig. 2 but 25 showing a modified form of door opening means embodying the present invention, the plunger unit of said means being carried by the automobile door, rather than by the automobile body portion on which said door is hinged.

30 Before the present invention is described in detail, it is to be understood that such invention is not limited to the details of construction or the specific arrangement of parts herein illustrated or described, as the invention obviously may take 35 other forms. It also is to be understood that the phraseology or terminology herein employed is for the purpose of description and not of limitation.

Although door opening means embodying the present invention are applicable for use with any hinged doors having their hinge edge walls oppositely positioned or in generally abutting relationship with respect to the hinge edge walls of their supporting structures (the structures on 45 which said doors are hinged), said door opening means are particularly useful, as heretofore pointed out, with the doors of automobiles or the like, and for purposes of illustration and not of limitation, the use of two such door opening 50 means with present-day automobile doors is here shown and described.

Referring first to Figs 1 to 5 inclusive, wherein is illustrated one form of door opening means embodying the present invention, the reference numeral 1 designates a portion of a left front automobile door, said door having its transverse front edge wall 2 suitably hinged, as is usual, on the transverse rear edge wall 3 of that portion of the automobile body shown in Figs. 1 to 3 inclusive and designated generally by the reference numeral 4, a pair of concealed hinges 5 being used for that purpose and the hinge axis 6 of said door being indicated in Figs. 1 and 2. As best shown in Fig. 2, when the door 1 is in its closed 65 position, the door and body edge walls 2 and 3 (which edge walls are hereinafter termed "hinge edge walls") are in oppositely positioned or generally abutting relationship, by which is meant that such hinge edge walls are oppositely positioned or disposed and either in actual contact or, as here shown, relatively close to each other.

Although any suitable means may be utilized for releasably retaining the door 1 in its closed position and for actuating said retaining means 70 to release said door for opening movement, (said

retaining means being hereinafter referred to broadly as "latch means"), the door opening means here involved are particularly useful in conjunction with doors whose latch means have pushbuttons or the like for effecting release actuation thereof, as said door opening means automatically effect the opening of such doors upon the unlatching thereof. Projecting door handles, by the use of which present-day automobile doors are unlatched and manually opened, not only are 10 dangerous (in that many severe injuries have been caused by them) but also, said projecting handles seriously interfere with the streamlining effects now desired for automobile bodies. Inasmuch as the door opening means here involved 15 automatically effect, upon the unlatching of the doors with which they are used, the movement of said doors to any desired open positions, including their fully open positions, the use for such doors of the present-day handles for door opening purposes is wholly unnecessary. As a result, simple push-buttons or the like, desirable from many standpoints, may be used with the latch means of a door with which is used a door opening means embodying the present invention. 25

The latch means, therefore, of the automobile door 1 may be, and preferably is, of the type in which push-buttons or the like are utilized for effecting the release actuation of said latch means. For example, said latch means may be 30 of the form disclosed in my copending application for Door opening devices, filed August 21, 1939, Serial No. 291,240, or in other words, latch means embodying the invention of my prior Patent No. 2,094,413 for Door control mechanism, 35 to which patent reference may be had, if desired. However, inasmuch as the latch means of the door 1 forms no part of the present invention, no latch means for such door is here shown or described.

As will hereinafter more fully appear, each of the here illustrated door opening means is of simple and inexpensive character and capable of being located between the general planes of the inner and outer side walls of an automobile door and the general planes of the inner and outer side walls of that portion of the automobile body on which said door is hinged, there being (see Figs. 2 and 6) more or less alignment of the outer side wall of such a door and the outer side wall of such a body portion and more or less alignment of the inner side wall of such a door and the inner side wall of such a body portion, when said door is in its closed position.

As a result, each of the door opening means here illustrated not only is eminently satisfactory from structural and functional standpoints but also, is commercially practical for a present-day automobile door, as such means is concealed from view when said door is in its closed position and its location, and the extent of its exposure even when said door is in its fully open position, are such as to cause said means to be entirely unobjectionable.

Although door opening means embodying the present invention may take various forms, the two door opening means here shown, for purposes of illustration, each comprises a simple and inexpensive self-contained plunger unit carried by either the automobile door to be automatically opened or the automobile body portion on which said door is hinged, and an economically formed curved portion carried by the other and with which curved portion the plunger of said unit has cooperative engagement for door open- 75

ing and door retaining purposes, as will hereinafter appear. If said plunger unit is carried by the automobile body portion, as in that embodiment of the invention illustrated in Figs. 1 to 5 inclusive, the curved portion carried by the automobile door will be of concave form in cross-section, as best shown in Fig. 2, and if said plunger unit is carried by the automobile door, as in that embodiment of the present invention illustrated in Fig. 6, the curved portion carried by the automobile body portion will be of convex form in cross section, as clearly shown in Fig. 6.

As best shown in Fig. 2, the self-contained plunger unit 7 of the door opening means of Figs. 1 to 5 inclusive is secured to the automobile body portion 4 adjacent its hinge edge wall 3 and between the general planes of its inner and outer side walls 8 and 9, the general plane of each such side wall, as that term is here used, being the plane which not only includes such side wall but which also extends thereto. The concave portion 10 of the door 1 is located between the general planes of its inner and outer side walls 11 and 12, and although such concave portion may be in the form of an attachment for said door and suitably secured thereto, such as to the hinge edge wall 2 thereof, the concave portion 10 here shown is a simple depression of said door hinge edge wall.

As clearly indicated in Figs. 1 to 5 inclusive, the plunger unit 7 comprises simple and inexpensive parts capable of being easily and conveniently assembled as a unit, said parts being a bracket, a reciprocable plunger, and expansible means in the form of a coiled compression spring for maintaining the head of said plunger in cooperative engagement with the concave door portion 10.

As here shown, the bracket of said plunger unit comprises two like members, each being in the form of a simple sheet metal stamping and each having a semi-cylindrical hollow housing portion 13, an attaching flange portion 14, and a connecting web portion 15. In its assembled form, said bracket has its two housing portions in abutting relationship, its two web portions in like relationship, and its two flange portions in diverging relationship, said flange portions being here screwed or otherwise suitably secured to the hinge edge wall 3 of the automobile body portion 4. As clearly shown in Fig. 5, the two housing portions 13 of said bracket together form a tubular housing, within which are mounted, as will hereinafter appear, the aforesaid plunger and the coiled compression spring therefor, the front end of said housing being closed and the rear end thereof being open. As best shown in Fig. 2, the longitudinal axis of said housing is generally diagonal with respect to the inner and outer side walls 8 and 9 of the automobile body portion 4, and the open rear end of said housing terminates adjacent the outer longitudinal edge portion of the hinge edge wall 3 of said body portion, there being a suitable opening 16 in such hinge edge wall portion for the reception of the plunger which is slidably mounted in said housing. Although the length of said housing may be varied, as desired, the length of the present housing is such that a suitable opening 17 is necessary, for the reception of the front end portion of said housing, in the transverse wall 18 of the sheet metal reinforcement pillar 19 with which the automobile body portion 4 is here provided.

The plunger of said self-contained plunger unit is here shown as a simple metal tube 20, said tube being slidably mounted in said bracket housing and having its front end open and its rear end closed, as best shown in Fig. 2. If desired, the closed rear end of said plunger tube may be utilized as the head of the plunger and if it is, it preferably will be of more or less rounded form or be otherwise suitably shaped for its cooperative engagement with the concave door portion 10, as will be readily understood. As here shown, however, the head of the present plunger is a roller 21, which enables said plunger to have desirable rolling engagement with the concave door portion 10 during opening and closing movement of the door 1, said roller being journaled, as here shown, on a rivet 22 or the like which is carried by a pair of ears 23 suitably secured to the closed rear end of the plunger tube 20.

As best shown in Fig. 2, the coiled compression spring 25 of said plunger unit is located within the tubular bracket housing, and extends into the plunger tube 20 slidably mounted in said housing, the front end of said spring being in engagement with the closed front end of said housing and the rear end of said spring being in engagement with the closed rear end of said plunger tube. As a result, said spring constantly urges said plunger tube and its roller 21 rearwardly from said housing, and thus enables the cooperative engagement of said roller with the concave door portion 10 to automatically effect the opening of the door 1, as will hereinafter more fully appear. In order to limit the extent to which the plunger may rearwardly project from its bracket housing, and thereby maintain such parts at all times in their unitary relationship, the plunger tube 20 is here provided, adjacent its front end, with a lateral lug 26 which extends at all times into a longitudinally disposed slot 27 of the bracket housing, said slot being here formed by registering notches with which the outer longitudinal edges of the two bracket housing portions 13 are provided.

Although a door opening means embodying the present invention may effect, if desired and as hereinafter referred to, the automatic movement of the door with which it is used to a partially open position only, said door being manually movable to its fully open position, the automobile door 1 is here automatically movable to its fully open position by the door opening means of Figs. 1 to 5 inclusive, the fully open position of said door being determined by the door check 35 (not shown) with which said door, like all present-day automobile doors, is provided.

For the accomplishment of that result, and to enable the fully open position of the door 1 to correspond to the fully open position of an automobile door which is manually opened, the length or transverse extent of the concave portion 10 of the hinge edge wall 2 of the door 1 is here such that it is substantially equal to the width of said hinge edge wall, and the path of reciprocation of the plunger cooperable therewith is here such that the roller 21 of said plunger engages said concave door portion adjacent the outer end thereof when said door is in its closed position, as clearly shown in Fig. 2.

When the door 1 is in its closed position, the coiled compression spring 25 of the plunger unit is in its fully compressed or loaded condition, such compression or loading of said spring being effected during the manual closing of said door 75

through the engagement of the concave portion 10 of said door with the plunger roller 21. The effect of such engagement, as will be readily understood, is the movement of said roller and the plunger tube 20 forwardly with respect to the body bracket housing, and the consequent compression or loading of the spring 25 which is confined, as heretofore pointed out, between the front end of said bracket housing and the rear end of said plunger tube.

The compression spring 25 is therefore in condition, when the door 1 is in its closed position, to automatically effect, upon the unlatching of said door, the movement of said door to its fully open position, the expansion force of said spring being sufficient for such purpose. Inasmuch as the door 1 is moved by the present door opening means to its fully open position, the plunger roller 21 of such means remains at all times in cooperative engagement with the concave door portion 10, as clearly indicated in Fig. 2, wherein in three positions of said door, between its closed position and its fully open position, are shown in dotted lines, the fully open position of said door (a position which also is shown in dotted lines) being indicated by the reference letter A.

As best shown in Fig. 2, the concavity of the concave door portion 10 is such that the door opening force applied thereto by the plunger roller 21, under the influence of its compressed or loaded spring 25, is substantially normal at all times to said concave door portion, and as a result, the automatic opening movement of the door 1 is brought about in a particularly desirable and effective manner. Conversely, the spring loading force applied to the plunger roller 21 by the concave door portion 10, during manual closing movement of the door 1, is substantially normal to the path of reciprocation of said roller and the plunger tube 20 by which said roller is carried, so that said spring is compressed or loaded, during the closing of said door, in a particularly satisfactory manner, all as will be readily understood.

As heretofore indicated, the door opening means of Figs. 1 to 5 inclusive not only effects, upon the unlatching of the door 1, the automatic movement of said door to its fully open position but also, yieldingly resists the closing of said door from such position. As a result, said door is releasably held or retained in its fully open position whenever it is moved thereto, and no separate holding means for said door is therefore necessary. The door closing resistance provided by said door opening means is due, of course, to the compression resistance of its coiled compression spring 25, and as will be readily understood, the spring used in a door opening means embodying the present invention may have any desired compression resistance when the door with which it is used is in the open position to which it is automatically movable.

By varying the rearward extent of the bracket housing slot 27, or the location in said slot of the plunger lug 26, the extent of the rearward movement of the plunger roller 21, under the influence of the compression spring 25, and hence the extent of the automatic opening movement of the door 1, may be controlled and predetermined, as desired. Thus, the door opening means of Figs. 1 to 5 inclusive may be readily modified, if desired, to effect the automatic movement of the door 1, upon the unlatching thereof, to any predetermined partially open position, the door being manually movable, of course, to a further open

position, and closing movement of said door from the partially open position to which it is automatically movable, being yieldingly resisted. If the door 1 is to be automatically movable to a partially open position only, the length or transverse extent of the concave portion 10 of said door may be reduced, if desired, all as will be readily understood.

As heretofore pointed out, the reciprocable plunger of door opening means embodying the present invention may be carried, if desired, by the door to be automatically opened and cooperate, for door opening and door retaining purposes, with a convex portion (convex in cross-section) carried by the supporting structure for said door. Such a door opening means is illustrated in Fig. 6, and to avoid needless duplication, only the manner in which such door opening means differs from the door opening means of Figs. 1 to 5 inclusive will be referred to.

In the door opening means of Fig. 6 (Fig. 6 being a view generally corresponding to Fig. 2), the self-contained plunger unit is carried by a left front automobile door 1a, the reciprocable plunger roller 21a of said unit having cooperative engagement, for door opening and door retaining purposes, with a convex portion 10a (convex in cross-section) carried by the automobile body portion 4a on which said door is hinged, the hinge axis of said door being indicated by the reference designation 6a. As here shown, the bracket base flanges 14a of said plunger unit are welded or otherwise suitably secured to the inner side wall 11a of said door, with the disposition of the plunger tube 20a (by which the roller 21a is carried) such that the path of reciprocation of said plunger tube and its roller is more or less diagonal with respect to such door side wall. If desired and as here shown, the convex portion 10a of the automobile body portion 4a may be a simple projection of its hinge edge wall 3a, and to enable such body hinge edge wall and the hinge edge wall 2a of the door 1a to be relatively close to each other, when said door is in its closed position, the hinge edge wall of said door may be provided, as here shown, with a suitable pocket or cavity 30 for the reception of the convex body projection 10a when said door is closed, all as will be readily understood.

As here shown, the pocket or cavity 30 of said door is formed by suitably depressing a portion 31 of the hinge edge wall 2a of said door, said depressed portion 31 being provided with a suitable opening 16a for the reception of the plunger roller 21a.

Although the door opening means of Fig. 6 may effect, if desired, and as will be readily understood from the detailed description of the door opening means of Figs. 1 to 5 inclusive, the automatic movement of the door 1a to a partially open position only, said door is here automatically movable, by the door opening means of Fig. 6, to its fully open position, which is the dotted line position of said door indicated by the reference letter B.

Inasmuch as the door opening means of Fig. 6 operates in the same manner as the door opening means of Figs 1 to 5 inclusive, (the convexity of the convex portion 10a of the door opening means of Fig. 6 being such that the force applied thereto by the expansible means of its plunger unit is substantially normal to said convex portion at all times), no further reference to the door opening means of Fig. 6 is believed to be necessary.

Other features and advantages of the present invention will be readily apparent to those skilled in the art to which said invention relates.

What I claim is:

supporting structure therefor wherein said door structure is so hinged on said supporting structure that the hinge edge walls of said structures are in oppositely positioned relationship when 5 said door structure is in its closed position, a reciprocal element carried by one of said structures, and expansible means constantly urging said reciprocal element toward the hinge edge wall of said other structure, the hinge edge wall 10 of said last mentioned structure being provided between the general planes of the side walls of such structure with a transverse portion of convex form in cross-section for cooperative engagement with said reciprocal element, the force of 15 said expansible means effective upon said hinge edge wall and acting through said reciprocal element being sufficient to automatically bring about the movement of the door structure, if closed and unlatched, to an open position, the hinge edge wall of the structure which carries 20 said reciprocal element being provided between the general planes of the side walls of such structure with a depressed portion for the reception of said convex portion when said door structure is in its closed position, the convexity of said convex portion being such that the force applied thereto by said expansible means is substantially normal 25 thereto at all times.

8. In combination with a door structure and a supporting structure therefor wherein said door structure is so hinged on said supporting structure that the hinge edge walls of said structures are in oppositely positioned relationship when 5 said door structure is in its closed position, a reciprocal element carried by one of said structures, and expansible means constantly urging said reciprocal element toward the hinge edge wall of the other structure, the hinge edge wall 10 of said last mentioned structure having a transverse portion of concave form in cross-section and of substantially the full width of said hinge edge wall for cooperative engagement at all times with said reciprocal element, the force of said 15 expansible means effective upon the hinge edge wall of said last mentioned structure and acting through said reciprocal element being sufficient to automatically bring about the movement of the door structure, if closed and unlatched, to an open 20 position, the concavity of said concave portion being such that the force applied thereto by said expansible means is substantially normal thereto at all times and the path of reciprocation of said element being such that said element engages said 25 concave portion adjacent one end thereof when said door structure is in its closed position.

RUDOLPH I. SCHONITZER.
